(57) CLAIM

The ornamental design for a massage gun, as shown and described.

DESCRIPTION

FIG. 1 is a front, right side and top perspective view of a massage gun design showing my new design.

FIG. 2 is a rear, left side and bottom perspective view of a massage gun.

FIG. 3 is a front view of a massage gun.

FIG. 4 is a rear view of a massage gun.

FIG. 5 is a left side view of a massage gun.

FIG. 6 is a right side view of a massage gun.

FIG. 7 is a top view of a massage gun; and,

FIG. 8 is a bottom view of a massage gun.

The broken lines in the drawings depict portions of the massage gun that form no part of the claimed design.
